UNITED STATES PATENT OFFICE

161,989

VALVE

Herbert Allen, Houston, Tex., assignor to Cameron Iron Works, Inc., Houston, Tex., a corporation of Texas

Application December 30, 1949, Serial No. 6,931

Term of patent 14 years

(Cl. D78—1)

To all whom it may concern:

Be it known that I, Herbert Allen, a citizen of the United States, residing at Houston, in the county of Harris, State of Texas, have invented a new, original, and ornamental Design for a Valve, of which the following is a specification, reference being had to the accompanying drawings, forming a part hereof.

Fig. 1 is a perspective view of a valve on a slightly enlarged scale embodying my new design;

Fig. 2 is a front elevation of the valve shown in Fig. 1 upon a reduced scale;

Fig. 3 is a side elevation of the valve shown in the preceding figures and taken 90° to the valve shown in Fig. 2 from the right;

Fig. 4 is a side elevation of the valve shown in the preceding figures illustrating the opposite side to that shown in Fig. 2;

Fig. 5 is a bottom plan view of the valve shown in the preceding figures; and

Fig. 6 is a top plan view of the valve shown in the preceding figures.

What is claimed is:

The ornamental design for a valve, substantially as shown.

HERBERT ALLEN.
